BOWLING BALL RETURN

Marjory K. Martin, Shelby, Ohio

Application January 6, 1956, Serial No. 39,637

Term of patent 14 years

(Cl. D34—5)

FIG.1

FIG.2

Figure 1 is a perspective side elevation of a bowling ball return embodying my new design.

Figure 2 is a perspective end elevation of the bowling ball return shown in Figure 1.

I claim:

The ornamental design for a bowling ball return, as shown.
